UNITED STATES PATENT OFFICE

JOHN M. KEOWN, OF CHICAGO, ILLINOIS, ASSIGNOR OF ONE-FIFTH TO ARTHUR E. SANGDAHL, OF WESTERN SPRINGS, ILLINOIS, ONE-FIFTH TO W. FOREST OGLE, OF CHICAGO, ILLINOIS, ONE-FIFTH TO EDWIN J. LEARNED, OF LAKE FOREST, ILLINOIS, AND ONE-FIFTH TO BENTLEY F. RAMSDELL, OF GENEVA, ILLINOIS

GRATING

Original application filed September 6, 1929, Serial No. 390,704. Divided and this application filed December 10, 1931. Serial No. 580,042.

This invention relates to a new and improved construction for gratings, such as floor gratings, and the present application is a division from my copending application 5 Serial No. 390,704, filed September 6, 1929.

A general object of the invention is the provision of a grating construction which will have desired strength and durability, and which can be manufactured economically and without waste of material. 10

A more specific object is the provision of a grating construction wherein the parts are permanently connected by forging operations.

Another specific object is the provision of a grating construction wherein the component parts of the grating are so connected as to prevent rusting in the joints and consequent loosening of the parts and weakening of the structure. 15

Yet another specific object is the provision of a grating wherein simple commercial shapes may be employed throughout in the grating construction.

Another particular object of the invention is the provision of a grating construction wherein the strength and stiffness of the component parts are maintained and utilized to the best advantage. 20

Other and further objects will be pointed out or indicated hereinafter, or will be apparent to one skilled in the art upon an understanding of the invention or its employment in practice. 25

In the following description and in the drawing forming part of this specification, the invention is explained through the disclosure of certain examples, but it is to be understood that these are presented for the 30

purpose of illustration merely, and are not to be construed in any fashion calculated to limit the appended claims short of the true and most comprehensive scope of the invention in the art. 35

In said drawing,

Fig. 1 is a perspective view of a portion of the completed grating;

Fig. 2 is a section along the line 2—2 of 40 Fig. 1; and

Fig. 3 is a section along the line 3—3 of Fig. 1.

Gratings suitable for use as supporting surfaces, such as floor gratings, stair treads, walk ways, platforms, and the like, must possess the necessary strength and stiffness to support considerable loads, the stability or permanency of jointing or connection of component parts such as to prevent their becoming loosened under repeated pressure and permitting rattling and weaving, and they must also lend themselves to pleasing and uniform design and to various dimensional requirements and accommodation of portions of a building structure in association with which they are to be installed. Economical manufacture is of very distinct importance, particularly as related to quantity production. 55 60 65

The present invention provides a grating which satisfies these requirements in a very effective manner. It involves the use of only the simplest commercial rolled shapes of bars, and operations which may be performed automatically with rapidity and certainty. 70 Described generally, the invention contemplates the provision of a plurality of carrier bars, in the form of relatively flat strips, which are punched at suitable intervals for the reception of connecting bars, which may be round, square or of other appropriate cross section, and which are threaded through the punched openings in the carrier bars, the latter being arranged in parallel relationship at suitably spaced intervals. The portions of the connecting bars between the carrier bars are re-formed in such fashion that the bars are permanently connected together, the ends of the connecting bars being upset upon the outer sides of the outermost carrier 75 80 85 bars, and portions of the connecting bars being formed out flush with the margins of the carrier bars on the side of the grating which is to be the top or tread side when it is installed for use. As a consequence, the 90 strength and stiffness of the material is availed of to the best advantage and a stiff and rigid structure having moisture-proof joints is formed. 95

The invention will be understood more in 100

detail by reference to the example of structure illustrated in the drawing. A suitable number of flat carrier bars 10, of steel or other suitable material, are punched at desired intervals, preferably to one side of their neutral axis, to afford apertures 11 which are entirely between the margins of the bars, so that they are completely surrounded by the metal. Although indicated at 11 as of square form, these apertures may be of other suitable shape. The carrier bars being arranged in parallel collateral relationship, connecting bars 12, preferably of a cross-section which fits the apertures 11 with an easy sliding fit, are inserted through the aligned apertures of the carrier bars, the ends of the connecting bars being projected slightly beyond the outermost carrier bars. These bars originally may be of square, circular, or other appropriate cross-section. The network of bars being thus loosely assembled, the connecting bars are heated to a temperature which will permit of their being readily forged, and the portions of the connecting bars are then subjected to a forging or swaging operation by which said portions of the connecting bars between the carrier bars are re-formed by pressures applied transversely of said portions. In this re-forming operation the carrier bars are supported on a rigid plane surfaced table and some of the metal of the connecting bars is displaced beyond the upper and lower margins of the apertures 11 so that it overlaps opposite side portions of the carrier bars, and some of the metal is also forced longitudinally of the connecting bars so that the apertures 11 are completely and tightly filled, and fillets 17 are formed in the angles between the carrier bars and connecting bars. At the same time the projecting ends of the connecting bars are upset so as to head them over on the outer sides of the outermost carrier bars, forming the heads 12a. During these re-forming operations, the carrier bars are held closely in contact with the table by suitable holding-down pressure. In the re-forming of the connecting bars, portions of the metal thereof are pressed down closely into contact with the table surface, thus forming margins on the connecting bars which are flush with the margins of the carrier bars which are in contact with the table surface. In order to insure the proper displacement of the metal of the connecting bars into contact with the table surface, it may be desirable to apply the forging pressures obliquely, so as to give the carrier bar portions a slightly tapering cross-section, approximately as illustrated. By use of suitable material for the connecting bars, and adequate pressure, it is apparent that this re-forming of the bars may be effected without the preliminary heating of them.

55 The re-forming of the connecting bars in

the manner described effects a permanent connection of all of the bars in the grating structure, producing a practically integral fabric in which all of the bars are definitely held against shifting relative to one another. 70 The joints between the carrier bars and connecting bars, being formed under compression, may be made sufficiently close to prevent entrance of moisture. Hence, rusting in the joints may be definitely prevented, 75 and the bars thus safeguarded against loosening in such fashion as to permit their rattling or to permit the structure weaving. During the intermittent feeding of the fabric to the forging operation, and during the re-forming of the connecting bars, the carrier bars are supported and guided in the desired spacing and parallel relationship. 80

The grating thus formed, which is illustrated in Figs. 1, 2 and 3, possesses very marked strength, stiffness and stability. The side of the grating which in the forging operation was in contact with the table, constitutes the upper or tread surface of the finished structure. Stiffness is effected in the structure by the closeness of the joints, the continuity of the connecting bars and the overlapping of the re-formed portions of the connecting bars on the sides of the carrier bars, said portions acting as struts holding the carrier bars against tilting laterally, and thus maintaining their major radius in the line of thrust of loads imposed on the tread side of the grating. The strength and stiffness are also contributed, in part, by the fact that the integrity of the marginal portions of the carrier bars is maintained throughout their length, and the section modulus of the carrier bars, on the compression side of their neutral axis, is preserved by the compact filling of the apertures 11 by the metal of the connecting bars. By virtue of the strength, stability and stiffness of the structure, gratings of this construction are well qualified for the supporting of heavy loads, such as may be imposed upon them in their use as floor gratings, platforms and the like. The grating may be constructed, of course, with any desired spacing of the carrier bars and the connecting bars, and presents a regular and workmanlike design. 100

What I claim is:

1. A grating comprising a plurality of collaterally spaced carrier bars having transverse apertures located in their compression portions and spaced from their margins and a plurality of solid metal connecting bars each extending through and solidly filling apertures in a plurality of the carrier bars, portions of said connecting bars at opposite sides of the carrier bars being of cross-sectional form different from the shape of the apertures and having abutting contact with opposite lateral surfaces of the carrier bars. 110

for a substantial portion of the depth of said portions.

2. A grating section comprising a plurality of carrier bars arranged in collaterally spaced relationship and having transverse apertures spaced from their margins, a plurality of solid metal connecting bars each extending through apertures in all of the carrier bars of the section, said connecting bars having their portions between the carrier bars of cross-sectional form different from the form of the apertures and abutting the opposite lateral surfaces of respective carrier bars at an appreciable distance from the apertures.

3. A grating comprising a plurality of carrier bars extending in collateral spaced relationship and having transverse apertures spaced entirely from their margins, and a plurality of solid metal connecting bars each extending through an aperture in one of the carrier bars and through aligned apertures in a plurality of the other carrier bars and having portions solidly filling said apertures, said connecting bars having their portions between the carrier bars of cross-sectional form different from the form of the apertures and abutting lateral faces of the carrier bars for an appreciable distance at opposite sides of the apertures.

4. A grating comprising a group of carrier bars arranged collaterally on edge in spaced relationship, said carrier bars being provided with transverse apertures, and a plurality of solid metal connecting bars each extending from one carrier bar to another through apertures in intervening carrier bars, said connecting bars having their portions intermediate the carrier bars of a depth exceeding the height of the apertures and abutting the sides of the carrier bars for an appreciable part of their depth in a manner to hold the carrier bars against tilting laterally.

45 5. A grating comprising carrier bars arranged collaterally in spaced relationship and provided with transversely extending apertures spaced from their margins, and connecting bars of solid metal cross-section each extending through apertures in a plurality of the carrier bars and having portions entirely filling said apertures and spacer portions abutting lateral faces of the carrier bars for an appreciable distance beyond the margins of the apertures, said spacer portions of respective connecting bars being in alignment transversely of the carrier bars.

60 6. A grating comprising a group of carrier bars disposed collaterally in spaced relationship and having aligned transverse apertures, and a plurality of solid metal connecting bars each extending through aligned apertures in a plurality of pairs of the carrier bars and completely filling the apertures in which they are positioned, said connect-

ing bars also having spacer portions intermediate the carrier bars of a cross-sectional form different from the form of the apertures and having end abutments with lateral faces of the carrier bars.

7. A grating comprising a plurality of carrier bars arranged in collaterally spaced relationship and provided with transverse apertures spaced entirely from their margins and located above their neutral axes, said carrier bars having their upper margins approximately in a common plane, and a plurality of solid metal connecting bars extending transversely of the carrier bars through the apertures therein, said connecting bars having their portions within the apertures entirely filling the same and their portions intermediate the carrier bars of cross-sectional form different from the form of the apertures and with parts thereof in approximately the same plane as the upper margins of the carrier bars, the portions of respective connecting bars intermediate the carrier bars being in alignment transversely of the carrier bars and having abutment with lateral surfaces of the latter for an appreciable distance from the apertures.

8. A grating comprising a plurality of carrier bars arranged collaterally in spaced relationship, said carrier bars having transverse apertures spaced from their margins, and a plurality of connecting bars each extending through apertures in a plurality of the carrier bars and having portions compressed in and completely filling such apertures, said connecting bars having their several portions between the carrier bars re-formed throughout their length and into abutment with lateral surfaces of the carrier bars at an appreciable distance from the apertures.

9. A grating as specified in claim 8 and wherein portions of the connecting bars between the carrier bars are in approximately the same plane as the upper margins of the carrier bars.

10. A grating as specified in claim 8 and wherein the said apertures are located above the neutral axis of the carrier bars.

In testimony whereof I have hereunto subscribed my name.

CERTIFICATE OF CORRECTION.

Patent No. 1,867,702.

July 19, 1932.

JOHN M. KEOWN.

It is hereby certified that error appears in the printed specification of the above numbered patent requiring correction as follows: Page 3, line 1, claim 1, for the word "portion" read proportion; and that the said Letters Patent should be read with this correction therein that the same may conform to the record of the case in the Patent Office.

Signed and sealed this 15th day of November, A. D. 1932.

(Seal)

M. J. Moore,
Acting Commissioner of Patents.
